UNITED STATES PATENT OFFICE.

OSCAR F. JACOBSON, OF GARFIELD TOWNSHIP, CLAY COUNTY, KANSAS.

METAL SHINGLE.

1,076,123.

Specification of Letters Patent.

Patented Oct. 21, 1913.

Application filed September 3, 1912. Serial No. 718,218.

To all whom it may concern:

Be it known that I, OSCAR F. JACOBSON, a citizen of the United States, residing in Garfield township, in the county of Clay and State of Kansas, have invented new and useful Improvements in Metal Shingles, of which the following is a specification.

My invention relates to metal shingles for application to roofs of buildings and for other purposes and is designed to prevent water or other liquid from flowing or leaking through between the overlapping ends of the shingles. I attain these objects by means of the construction illustrated in the accompanying drawing, in which—

Figure 1 is a perspective view of a series of shingles constructed in accordance with my improved method and fitted together as when on the roof of a building; Fig. 2, an end elevation thereof; Fig. 3, a side elevation of a longitudinal section through the middle portion of the shingles; Fig. 4, a side elevation of a longitudinal section in line with the edge of the projection 8, and Fig. 5, a detail view in perspective of my improved shingle.

Similar numerals of reference indicate like parts throughout the several views.

Full length shingles are indicated by the numeral 1, the bottom half-course by 1^a and the top half-course by 1^b.

2 is the edge of a "raised seam"; 3, the flange at the outer edge of each shingle; 4, a slit cut in the edge thereof at approximately midway of its length; 5, the end folded under and 6, the end folded over; 7, the projections formed in beveling the ends of the folded part 6, such beveling being for the purpose of facilitating joining; 8, the projections formed in cutting in to make the folded end 5.

It is common to join metal shingles by longitudinal ridges and grooves, forming

what is known as "raised seams" and leaving the ends merely overlapping or to be 45 soldered. But I propose to so construct my shingles that the folded ends may be interlocked and hammered together, thus forming a reasonably tight joint to resist the back flow and prevent leaking. 50

In laying my improved shingles the bottom course is laid in the usual manner with the overlap fold 6 uppermost at the upper end of the shingle. The next course is so laid that the underlap fold 5 engages the 55 overlap fold 6 and the shingles pulled snugly into position with the end of the overlap 6 engaging the slot 4 with the sides of each alternate layer exposed and of the other covered for approximately half their 60 length. The nailing of the shingles is done in the usual manner by driving the nails through the flanges 3 only where they will be covered by the overlapping portion of the next course. At the proper time all seams 65 and joints are securely pressed or hammered together in the usual manner.

Having thus described my invention what I claim as new and desire to secure by Letters-Patent is—

A metal shingle having one of its ends folded over and its other end folded under so that each layer may be interlocked with the layer abutting therewith, said shingle being provided with slits midway thereof 75 which extend in from the sides thereof, the portion above said slits being adapted to engage over the turned over portion of an adjacent shingle and the portion below said slits being adapted to engage under said 80 turned over portion of said adjacent shingle.

OSCAR F. JACOBSON.
